CLAIM

The ornamental design for a carrying case for tape cartridges and cassettes, substantially as shown and described.

DESCRIPTION

FIG. 1 is a perspective view of a carrying case for tape cartridges and cassettes showing my new design with the lid in an open position, the inside rear wall, and the opposite side of the central partition being identical to the sides shown;

FIG. 2 is a top plan view with the lid in closed position;

FIG. 3 is a front elevational view thereof;

FIG. 4 is a side elevational view thereof; and,

FIG. 5 is a bottom plan view.
